UNITED STATES PATENT OFFICE.

DOUGLAS H. DUER, OF BALTIMORE, MARYLAND.

SASH-CORD GUIDE.

SPECIFICATION forming part of Letters Patent No. 230,408, dated July 27, 1880.

Application filed April 14, 1880. (Model.)

To all whom it may concern:

Be it known that I, DOUGLAS H. DUER, of Baltimore city, State of Maryland, have invented certain new and useful Improvements 5 in Sash-Cord Guides; and I hereby declare the same to be fully, clearly, and exactly described as follows, reference being had to the accompanying drawings, in which—

Figure 1 is a side elevation of the device 10 inserted in the peculiar mortise adapted for its reception. Fig. 2 is a rear elevation of the device.

My invention has reference to sash-cord guides or sash-pulleys, and it has for its object to so construct the casing which carries 15 the sheave as to afford the greatest facility for inserting the guide in the window-frame, adapting the shape of the sheave to a mortise of predetermined and peculiar construction. The said mortise is cut by means of a laterally-moving bit long enough to completely 20 perforate the window-frame, and having a shoulder or spur at the proper distance from its point to countersink a groove for the reception of the face-flange of the sash cord 25 guide.

In the accompanying drawings, A is the casing, having rounded ends b b and a face-flange, a, of uniform width and extending 30 completely around the guide, the ends a' being rounded, as shown. D is the sheave, mounted on a pivot-pin, d. The bottom of the casing is provided with a spur, c, to engage with the bottom of the mortise, and the 35 upper end of the casing is perforated, as shown at e, a barbed-wire nail, C, being driven through the hole.

It will be seen that the mortise may be formed by any of the well-known mortising- 40 machines, it being only necessary to provide the machine with the spurred laterally-cutting bit and present the window-frame to it, or vice versa, until the bit has perforated the frame and its spur has sunk to the depth of 45 the flange a', a suitable stop being, of course, used to limit the motion. The frame is then simply moved at right angles to the bit until the mortise cut thereby is of the exact length 50 of the casing A, when the frame is withdrawn, the mortise being completed. It is obvious that these motions may both be made by either bit or frame-carriage, or either by either.

To insert the casing in the mortise the 55 lower end of the device is laid in place, with

the spur resting against the bottom of the mortise, the face of the casing being slightly inclined to the face of the window-frame. A tap of a hammer on the top of the casing causes the spur to enter the wood, and admits of the casing being pressed into the mortise flush with the window-frame. It is then secured by a barbed-wire nail or screw, C, inserted through the hole e.

Instead of the spur c, a second nail may be 65 inserted through the bottom of the device, or, in lieu of both, barbs may be formed on the sides or ends of the casing, the entering-marks of which will be concealed by the face-flange. 70

Now, from the foregoing description of the construction and mode of operation of the device it will be seen that its essential features are, first, a face-flange to prevent it from entering the mortise beyond the face of 75 the window-frame; second, that this flange shall have curved or semicircular ends and be of uniform width all round; and, third, that the device be provided with means for securing it in the window-frame. The first 80 two essentials are dependent upon the peculiar formation of the mortise as made in the manner and by the spurred bit described.

The device, when in place, has a neat and symmetrical appearance by reason of the even 85 and uniform approximation of its central aperture to the edge all round and the concealment of the fastening devices.

What I claim is—

1. A sash-cord guide having a face-flange 90 of uniform width all around and rounded at the ends, whereby the device is adapted for insertion in a mortise formed by a spurred laterally-cutting bit, as set forth.

2. A sash-cord guide having rounded ends 95 provided with a spur and perforation, or their specified equivalents, and having a face-flange of uniform width around the casing, as set forth.

3. The sash-cord guide herein described, 100 consisting of the sheave and casing, the latter having a face-flange of uniform width all around and rounded ends, one of which is provided with a spur and the other with a perforation in the rear of the flange, as set 105 forth.

DOUGLAS H. DUER.
